UNITED STATES PATENT OFFICE.

ERNEST OLDENBUSCH, OF NEW YORK, N. Y.

DESIGN FOR A TOILET-POWDER DISPENSER.

43,055.

Specification for Design.

Patented Sept. 24, 1912.

Application filed April 3, 1912. Serial No. 688,306. Term of patent 7 years.

To all whom it may concern:

Be it known that I, ERNEST OLDENBUSCH, a citizen of the United States, and residing at the city of New York, borough of Brooklyn, in the county of Kings and State of New York, have invented a new, original, and ornamental Design for a Toilet-Powder Dispenser, of which the following is a specification.

Reference is to be had to the accompanying drawing, in which—

Figure 1 shows my improved design in front elevation, and Fig. 2 shows the same in side elevation.

I claim:

The ornamental design for a toilet powder dispenser, as shown.

ERNEST OLDENBUSCH.

Witnesses:

F. M. VAN HOUTEN,
NELSON H. STEWART.
